UNITED STATES PATENT OFFICE.

FRANK A. RAPPLEYE, OF SILVER CREEK, NEW YORK, ASSIGNOR TO ALLEN & CO. INC., OF NEW HAVEN, CONNECTICUT, A CORPORATION.

SAW JOINTER.

Application filed March 2, 1922. Serial No. 540,466.

To all whom it may concern:

Be it known that I, FRANK A. RAPPLEYE, a citizen of the United States, residing at Silver Creek, in the county of Chautauqua and State of New York, have invented a new and useful Improvement in Saw Jointers; and I do hereby declare the following, when taken in connection with the accompanying drawings and the characters of reference marked theron, to be a full, clear, and exact description of the same, and which said drawings constitute part of this application, and represent, in—

Fig. 1 a perspective view of a saw jointer constructed in accordance with my invention, with the file removed.

Fig. 2 a side view of the same, with the file inserted.

Fig. 3 an end view of the same.

This invention relates to improvement in saw jointers, that is, a device for holding a file in proper position to coact with the edge of the saw in jointing the same, the object of the invention being a simple arrangement, whereby an ordinary, three-cornered file may be firmly held in proper position, and the invention consists in the construction as hereinafter described and particularly recited in the claim.

In carrying out my invention, I employ a strip 5 of spring sheet metal, the central portion of which is longitudinally bowed and formed with a longitudinal slot 6. The ends 7 and 8 are turned downward and formed with triangular holes 9 and 10, cor-

responding to the size of the file 11 to be used, and entering the ends and intersecting the holes are slots 12 and 13.

To insert a file, the ends 7 and 8 are pressed toward each other, so as to bring the holes 9 and 10 into alignment, and so that the file may be passed through the holes with one of its flat faces downward, the slot 6 giving clearance for the upper edge of the file. When the file is properly inserted, the ends are released, and as they spring outward they come to a bearing on the file, which is thereby firmly gripped. A saw is jointed in the usual way by inserting it into the slots 12 and 13 and moving the saw 50 or moving the jointer back and forth so as to true the cutting-edge.

This device is easily formed by stamping, and thus can be produced at very low cost and can be used with any suitable file.

I claim:

A saw jointer formed from a single strip of spring sheet metal, the central portion of which is longitudinally-slotted and bowed, the ends of the strip formed with triangular openings and with slots entering the ends of the strip and intersecting the said openings.

In testimony whereof, I have signed this specification in the presence of two subscribing witnesses.

FRANK A. RAPPLEYE.

Witnesses:

NELLIE DEVER,
MORRIS E. CLUTE.
